[57] CLAIM

The ornamental design for a combined portable spot and flood light, as shown and described.

DESCRIPTION

FIG. 1 is an isometric view of a combined portable spot and flood light showing my new design.

FIG. 2 is a top view of the light shown in FIG. 1, on an enlarged scale.

FIG. 3 is a side view of the light on an enlarged scale; the opposite side being identical except for the omission of the switch.

FIG. 4 is a bottom view of the light, on an enlarged scale.

FIG. 5 is an end view as seen from the left of FIG. 1, on an enlarged scale.

FIG. 6 is a view of the end opposite that shown in FIG. 5.
